METHOD OF ATTACHING SOLES
TO SHOESMax W. Tetlow, Boston, Mass., assignor to United
Shoe Machinery Corporation, Paterson, N. J.,
a corporation of New Jersey

Application December 7, 1932, Serial No. 646,157

33 Claims. (Cl. 12—142)

This invention relates to improvements in methods of attaching soles to shoes, and to improvements in shoes and shank pieces therefor.

Considerable difficulty has been experienced, particularly in the manufacture of shoes having cement-attached soles, in securing satisfactory attachment of the tread soles in the shank portions of the shoes and various attempts have been made to provide for additional security of attachment in that locality.

One object of the present invention is to improve the attachment of soles at the shank portions of shoes.

With this object in view, the invention provides an improved method of sole attaching which, as herein exemplified, contemplates securing together the intramarginal shank portion of a tread sole and a shank piece attached to the bottom of a shoe by means of cement produced by the action of a solvent upon fibrous material, for example fibrous cellulose derivative, applied between the tread sole and the shank piece. Preferably, and as illustrated herein, fibrous cellulose derivative is applied also between the shank piece and the shoe bottom and is converted into cement by the action of a solvent to secure the shank piece to the shoe bottom as well as to the tread sole. As herein exemplified, acetone is employed as the solvent and the fibrous cellulose derivative consists of textile fabric composed of braided cellulose ester fibers, for example cellulose acetate fibers, the fabric being made in the form of a tubular sheath-like covering which is shaped to fit the shank piece and which is slipped over the latter before it is applied to the shoe. Instead of being braided, the fibrous covering material may be woven, knitted, felted or otherwise formed and, as illustrated, the material is loosely fabricated so as to provide an absorbent fabric, i. e., a fabric which is readily soluble, for example, in acetone or other commercially available organic solvent. If desired, also, the covering material may be reinforced with fibers, for example cotton fibers, which are insoluble in or inert with respect to the solvent which is used.

In accordance with one method of carrying out the invention a covered shank piece is first dipped in a solvent so as to soften the cellulose derivative covering and render it plastic and thereafter the shank piece is positioned upon the shoe bottom and an outside is cement-attached in the usual manner, the pressure of the sole-attaching operation resulting not only in the cement attachment of the sole margins to the shoe bottom but also in the cement attach-

ment of the intramarginal shank portion of the sole to the shank piece and of the shank piece itself to the shoe bottom.

It may be desirable to permit the softened shank piece covering to dry, at least partially, before the outsole is applied and thus to provide for a firmer attachment of the shank piece to the shoe bottom so as to insure against possibility of the shank piece being displaced during subsequent sole-attaching operations. In such a case the shank piece covering will again be softened, as by the application of solvent thereto, just prior to the attaching of the outsole. In cases where the shoe parts have been preliminarily prepared for adhesive attachment of the outsole to the shoe as, for example, by having a coating of pyroxylin cement applied to the overlasted upper margins and to the margin of the outsole, or by having a strip of cellulose ester braid applied, either to the sole margin or to the upper margins, in accordance with the practice disclosed in my copending application serial No. 630,776, filed August 29, 1932, the cement coating will be activated or the cellulose ester braid will be softened by the application of solvent thereto before the outsole is applied. In such cases it has sometimes been found practicable to dispense with a second application of solvent directly to the shank piece covering inasmuch as a sufficient amount of solvent will usually be squeezed or forced inwardly from the cement-coated surfaces of the upper and outsole to insure suitable softening of the shank piece covering. It may even be practicable to rely upon this inward displacement of excess solvent from the margins of the upper and outsole to soften the shank piece covering upon both sides of the shank piece so that the shank piece may be laid in place upon the shoe bottom without any preliminary application of solvent thereto, the solvent displaced inwardly by the pressure of the sole attaching operation serving to condition the shank piece covering for the attachment of the shank piece to the shoe bottom or insole as well as to the outsole. If the shank piece is to be applied to the insole without first having had its covering softened, the shank piece may be held in place by means of tacks or other fastenings driven into the insole, such fastenings serving also as an additional means for preventing displacement of the shank piece during the wearing of the shoe.

Considered in another aspect, the invention consists in a shank piece covered with fabric capable of coating with a solvent to produce cement thereby adapting the shank piece for use in the

practice of the above-described method. The illustrated shank piece is provided with a fabricated, tubular, sheath-like covering of cellulose ester fibers. The shank piece covering may include also reinforcing threads or fibers of cotton, linen or other material which is insoluble in commercially available organic solvents and advantageously these reinforcing fibers may be secured to the shank piece by means of adhesive produced by the action of a solvent upon the cellulose ester fibers.

The invention further includes, as an article of manufacture, a tubular shank piece cover of cellulose derivative fabric.

13 Invention is still further to be recognized as residing in a shoe comprising an upper, a shoe bottom member, a tread sole, and a shank piece secured to the shoe bottom member and to the tread sole by a covering of cellulose derivative.

20 The invention in its various aspects will be described with reference to the accompanying drawing, in which

25 Fig. 1 is a perspective view of a tubular shank piece covering of loosely braided cellulose ester fabric embodying a feature of the present invention;

Fig. 2 is a sectional view, on an enlarged scale, taken along the line II—II of Fig. 1;

30 Fig. 3 is a perspective view of a shank piece having a tubular covering thereon of the type shown in Fig. 1;

Fig. 4 is a sectional view on an enlarged scale taken along the line IV—IV of Fig. 3;

35 Fig. 5 is a perspective view of a shoe bottom prepared for the attachment of an outsole in accordance with the method of the present invention;

Fig. 6 is a perspective view of an outsole molded or conformed to fit the bottom of the shoe of Fig. 5 and prepared for cement attachment to the 40 shoe;

Fig. 7 is a perspective view of a portion of a shoe bottom prepared for the attachment of an outsole in accordance with a method constituting a modification of that exemplified by Fig. 5; and

45 Fig. 8 is a cross-sectional view of the shoe as it appears when completed.

In practising the method of my invention, as herein exemplified, a shoe bottom and an outsole are prepared in the usual manner for the cement attachment of the sole to the shoe. Thus, a shoe 50 10 is shown in Fig. 5 as being mounted upon a last 12 and having the marginal portions 14 of the upper overlasted upon an insole 16 and secured in 55 lasted relation at the toe, for example, by cement, at the heel seat by tacks 18, and along the shank and opposite sides of the forepart by means of suitable fastenings, such as staples 20. To prepare the shoe bottom and the outsole for the 60 reception of the cement, the overlasted upper margins 14 and the marginal portions of the outsole 22 (Fig. 6) are roughened and coated with adhesive, such as pyroxylin cement, as herein indicated at 24 and 26, respectively. It is to be understood, however, that the invention is not necessarily restricted in its application to shoes having 65 cement-attached soles but is useful also in connection with the manufacture of shoes wherein the tread soles are attached by stitching or other fastenings. As illustrated, the outsole 22 has been 70 molded or conformed to fit the shoe bottom.

In accordance with the illustrated exemplification of my improved method I secure the intra-marginal shank portion of the outsole to the shoe bottom by means of cement produced by the 75 action of a solvent upon cellulose derivative dis-

posed between the outsole and a shank piece 30 and between the shank piece 30 and the shoe bottom, the cellulose derivative being preferably in the form of textile fabric composed of cellulose ester fibers, such as cellulose acetate or cellulose

5

nitrate fibers. Preferably the fibrous cellulose derivative is made in the form of a tubular sheath-like covering 32 for the shank piece, the latter being herein shown as consisting of cellulose ester fabric composed of loosely braided fibers so that an "openwork" covering is provided which may readily be acted upon by the solvent. Cellulose acetate fabric, for example, fabric made of the fiber available under the trade name "Celanese," is particularly useful for this purpose.

10

The cellulose ester fabric may be reinforced by fibers or strands of material, such as cotton, linen, etc., which is insoluble in the solvent used for the cellulose ester fibers. For convenience of description, the cellulose ester fibers will be referred to

15

hereinafter as "soluble" fibers, meaning fibers which are soluble in a selected solvent such as acetone, and the reinforcing fibers will be referred to as "insoluble" fibers, meaning fibers which are

20

insoluble in the particular solvent used for the cellulose ester fibers. In addition to strengthening the covering, the use of "insoluble" threads or fibers with the "soluble" fibers reduces the cost of

25

manufacture of the covering. Moreover, the presence in the completed shoe of the "insoluble" fibers encircling the shank piece tends to

30

strengthen the bond between the cement and the shank piece in a manner tending to prevent the hardened cement from breaking away from the shank piece during the wearing of the shoe.

35

Advantageously a substantial number of "insoluble" fibers may be employed, the fibers being braided, or otherwise fabricated, so that, after the "soluble" fibers have been converted into cement,

40

the shank piece will still be enveloped by a tubular fabric covering which will tend to make even more secure and lasting the attachment of the shank piece to the shoe. The covering may be

45

prevented from slipping off the shank piece during handling and shipment of the latter by a preliminary application to the covering of a sufficient quantity of solvent to cause the "insoluble" fibers

50

to adhere to the shank piece. Thus the shank piece may have a tubular covering of fabricated non-soluble fibers permanently secured thereto by means of cement derived from the "soluble" fibers

55

while the latter, being in a partially converted state and remaining at least partially intact, will function, when again softened after the shank piece has been placed in a shoe, to secure the shank piece and the "insoluble" portion of the

55

covering to the outer and inner soles of the shoe. It is believed that the presence, in the completed shoe, of the "insoluble" fibers or threads composing the shank piece covering, will tend also to prevent squeaking of the shoe.

60

The tubular covering 32 may be readily applied to the shank piece 30 by slipping the covering over the shank piece in the same manner as a

65

sheath is slipped over a knife, so as to produce a covered shank piece such as that shown in Figs. 3 and 4. In using the covered shank piece

70

to insure additional security in the attachment of the shank portion of an outsole, the shank piece is placed in the usual position in the shoe where the covering, after being converted into a

75

plastic cement-like mass by the action of a solvent thereon, will function both in securing the outsole to the shank stiffener and the shank stiffener to the insole.

75

I prefer to soften the shank piece covering by dipping the covered shank piece into a solvent, so that the covering will become substantially saturated with the solvent, before the shank piece is applied to the shoe. After being thus dipped, the covered shank piece may be manually placed upon the insole in the space between the overlasted upper margins, as illustrated in Fig. 5. The shank piece covering being semi-plastic at this time, due to the action of the solvent thereon, the slight pressure applied by the operator in laying the shank piece will serve to stick the shank piece in place sufficiently to hold it against accidental displacement during the operation of shoe bottom filling and during application of the outsole. The cement coating upon the overlasted and roughened upper margins 24 and/or upon the roughened margins 26 of the outsole 22 having been first activated by the application of solvent thereto in the customary manner, the outsole may now be cement-attached to the shoe by the use, for example, of a cement sole-attaching machine of the character disclosed in an application for Letters Patent of the United States, Serial No. 388,739, filed August 27, 1929, in the name of Milton H. Ballard. The cement produced by the action of the solvent upon the shank piece covering will be forced, by the sole-attaching pressure, into the form of layers interposed between the shank stiffener and the insole and between the shank stiffener and the outsole and, upon drying, the cement will serve effectively to secure the intramarginal shank portion of the outsole to the shoe bottom and also to reinforce and stiffen the shank portion of the shoe, without, however, interfering with the desired resilience thereof. Moreover, the cement, while plastic, will be squeezed or displaced outwardly by the sole-attaching pressure so as to fill all spaces between the stiffener and the edges of the upper margins so that no separate filling substance will be required in the shank portion of the shoe bottom. As a result of this action the shank stiffener will be embedded in cement in the finished shoe in such a manner as to insure against both endwise and lateral displacement of the shank stiffener throughout the life of the shoe.

In commercial practice it will undoubtedly be desirable to apply the covered shank pieces to the bottoms of a plurality of shoes before attaching the outsoles to any of them, in which case the cement produced by the action of the solvent upon the shank piece coverings will become partially or wholly dry before the shoes are ready to have the outsoles attached. Such drying of the cement is desirable inasmuch as the dried cement will serve to hold the shank pieces securely in place upon the shoe bottom so that they have no tendency to slip out of place during the sole-attaching operation. If the cement-like covering upon the shank stiffener is permitted to dry as above indicated, it may be reactivated by the action of the solvent applied either to the cement-coated upper margins or the outsole margins or to both the upper and outsole margins, that solvent being forced inwardly by the sole-laying pressure so as to engage and attach the shank piece covering. If desired, however, solvent may be applied directly to each shank piece covering just prior to the attaching of the outsole.

It may be found desirable to employ fastening means such, for example, as the tacks 34 (Fig. 7)

for securing the shank stiffener to the innersole prior to the application of the outersole, and in such cases it may be found practicable to secure the shank piece in place upon the insole without having first subjected the shank piece covering to the action of solvent and to rely upon a subsequent application of solvent to the exposed portion of the shank piece covering to soften not only the exposed portion of the covering but also the portion between the shank stiffener and the insole. In fact, it has been found that sufficient solvent may be squeezed inwardly from the marginal portions of the sole and upper to soften all portions of the shank piece covering without requiring any separate or manual application of solvent to the latter.

As will be readily appreciated, the herein-described method of attaching the intramarginal shank portions of soles to shoes insures greater security of attachment than has been possible heretofore in cases where there is no positive securing or bonding together of the tread sole and the shank piece and of the shank piece to the insole. Moreover, due to the secure attachment of the shank piece to both the inner and outer soles, and the filling in of all spaces between the soles along the lateral edges of the shank piece, there is no possibility of relative movement between the shank piece and the shoe bottom or between the shank portions of the inner and outer soles, during the wearing of the shoe and consequently possibility of squeaking is prevented and the correct shape of the shank portion of the shoe is preserved throughout the life of the shoe. This method of attachment of the shank portions of soles is particularly advantageous in shoes having unusually narrow shank portions, as in so-called "fiddle shank" shoes, where the absence of secure attachment of the intramarginal shank portions of the tread soles has been recognized heretofore as inherent weakness of construction.

Having described my invention, what I claim as new and desire to secure by Letters Patent of the United States is:

1. That improvement in methods of cement-attaching soles to shoes which consists in securing the intramarginal shank portion of a tread sole to a shoe by means of cement produced by the action of a solvent on fibrous cellulose derivative fabric disposed between the tread sole and a shank piece attached to the shoe bottom.

2. That improvement in methods of attaching soles to shoes which consists in securing the intramarginal shank portion of a tread sole to a shoe by means of adhesive produced by the action of a solvent on fibrous material disposed between the tread sole and a shank piece attached to the shoe bottom.

3. That improvement in methods of cement-attaching soles to shoes which consists in securing a shank piece to the bottom of a shoe, and securing the intramarginal shank portion of a tread sole to the shank piece by means of cement produced by the action of a solvent upon fibrous material applied between the shank piece and the shoe bottom and between the shank piece and the tread sole.

4. That improvement in methods of cement-attaching soles to shoes which consists in securing a shank piece to the bottom of a shoe, and securing the intramarginal shank portion of a tread sole to the shank piece by means of cement produced by the action of a solvent upon fibrous ma-

- terial applied between the shank piece and the shoe bottom.
5. That improvement in methods of attaching soles to shoes which consists in disposing fibrous cellulose derivative and a solvent therefor between a tread sole and a shank piece, and applying pressure to the sole and the shoe thereby causing the cement formed by the action of the solvent upon the cellulose derivative to stick the intramarginal portion of the tread sole to the shank piece. 10
6. That improvement in methods of making shoes which comprises disposing between a shank piece and a shoe bottom and between the shank piece and an outsole fibrous cellulose derivative treated with a solvent, and applying pressure to the shoe and the sole thereby causing the cement formed by the action of the solvent on the cellulose derivative to stick the shank piece to the shoe bottom and to the outsole. 15
7. That improvement in methods of making shoes which comprises applying cellulose ester fabric to both sides of a shank piece, positioning the shank piece upon the bottom of a shoe, treating the fabric with a solvent, and attaching an outsole while utilizing said treated fabric in securing the shank piece to the shoe bottom and the outsole to the shank piece. 20
8. That improvement in methods of cementing attaching soles to shoes which comprises securing to the bottom of a shoe a shank piece having a covering of cellulose derivative fabric, treating the fabric with a solvent therefor which by acting thereon will produce cement, positioning an outsole on the shoe bottom, and applying pressure to the shoe and the sole thereby causing the cement formed by the action of the solvent on the fabric to stick the sole to the shank piece. 25
9. That improvement in methods of cementing attaching soles to shoes which consists in covering a shank piece with cellulose ester fabric, applying a solvent to the fabric covering, applying the covered shank piece to the bottom of a shoe, positioning a tread sole upon the shoe bottom, and applying pressure to the shoe and the sole to attach the shank piece to the shoe bottom and the sole to the shank piece. 30
10. That improvement in methods of attaching soles to shoes which comprises covering a shank piece with tubular braid composed of cellulose ester fiber, dipping the covered shank piece in solvent, applying the shank piece to the shoe bottom, and cement-attaching the sole to the shoe thereby causing the shank piece to become attached to the shoe bottom and the sole to the shank piece. 35
11. That improvement in methods of cementing attaching soles to shoes which comprises covering a shank piece with tubular cellulose acetate braid, dipping the covered shank piece in solvent, laying the shank piece in place upon the shoe bottom, allowing the softened fabric to harden to attach the shank piece to the shoe bottom, thereafter applying solvent to the exposed side of the covered shank piece, positioning an outsole on the shoe bottom, and applying pressure to the shoe and to the sole to displace the softened fabric to fill the cavities in the shoe bottom and to attach the sole to the shank piece and the shank piece to the shoe bottom. 40
12. That improvement in methods of attaching soles to shoes which consists in applying to a shank piece a tubular covering of cellulose deriva-
- tive fabric, applying a solvent to said fabric covering, securing the shank piece in place upon the bottom of a shoe by means of the cement produced by the action of the solvent upon said fabric, applying an outsole to the shoe, and securing the outsole to said shank piece by means of said cement. 5
13. That improvement in methods of attaching soles to shoes which consists in inserting a shank piece into a tubular covering of cellulose nitrate fabric, positioning the shank piece in position upon the bottom of a shoe, applying a solvent to the fabric covering, positioning an outsole upon the shoe, and applying pressure to the outsole to effect the adhesive attachment of the shank piece to the shoe bottom and of the outsole to the shank piece by means of cement produced by the action of the solvent upon said fabric covering. 10
14. A shank piece covered with cellulose ester fabric. 20
15. A shank piece covered with fabric capable of coacting with a solvent to produce cement. 25
16. A shank piece covered with fabric soluble in acetone. 30
17. A shank piece covered with nitrocellulose fabric. 35
18. A shank piece covered with cellulose acetate fabric. 40
19. A shank piece enclosed within a tubular covering of cellulose derivative fabric. 45
20. A shank piece having a tubular covering of cellulose derivative fabric. 50
21. A shank piece having a tubular covering of cellulose acetate fabric. 55
22. A shank piece having a braided tubular covering of nitrocellulose fabric. 60
23. A shank piece having a covering of cellulose ester fabric in loosely braided form. 65
24. A shank piece having a covering composed of fibers of material soluble in a selected solvent to produce an adhesive reinforced by fibers of material insoluble in said solvent. 70
25. A shank piece having a covering composed of cellulose derivative fibers soluble in suitable organic solvents to produce an adhesive reinforced by cellulose fibers insoluble in said solvents. 75
26. A shank piece having a cover of fibrous cellulose derivative soluble in a selected solvent to produce an adhesive, said cover enveloping the shank piece and being secured to it by means of adhesive. 80
27. A shank piece having a tubular covering of cellulose derivative fibers soluble in a selected solvent to produce an adhesive and means securing said covering to the shank piece. 85
28. A shank piece having an enveloping fabricated covering composed of fibers soluble in organic solvents to produce an adhesive, and means fixedly securing said covering to the shank piece. 90
29. A tubular shank piece cover of cellulose derivative fabric. 95
30. A shank piece having a covering composed of material fabricated from fibers of cellulose acetate and cotton. 100
31. A tubular shank piece covering of textile fabric containing fibers capable of producing cement when acted upon by a solvent. 105
32. A fabricated shank piece cover composed of fibers of material soluble in a selected solvent to produce an adhesive and fibers of material insoluble in said solvent. 110
33. A shank piece having thereon an openwork adhesive-forming covering of cellulose derivative. 115
